UNITED STATES PATENT OFFICE.

JAMES S. HAGERTY, OF BALTIMORE, MARYLAND.

FOOT-BATH.

SPECIFICATION forming part of Letters Patent No. 226,063, dated March 30, 1880.

Application filed January 20, 1880.

To all whom it may concern:

Be it known that I, JAMES S. HAGERTY, of the city of Baltimore, in the State of Maryland, have invented certain Improvements in Foot-Baths, of which the following is a full, clear, and exact description, reference being had to the accompanying drawing, forming a part hereof.

The invention consists in extending upward 10 a long side of the foot-bath its entire length, whereby the bath, when used as a tray or rest for the slop-jar and bucket forming a set of chamber-furniture, may protect the wall against which it may be placed from water splashed 15 over the slop-jar in the act of emptying slop thereinto.

The drawing represents a perspective view of the invention.

The long side *a* of the foot-bath is extended 20 upward for its entire length, increasing in width as it rises by following the angle of the ends of the bath. The side *a* is made high enough to reach above the height of the slop-jar when standing within the foot-bath. The

width of the extended side is such as to completely protect the wall against the splashing of water thrown into the slop-jar, and also allows the user of the bath greater freedom without the danger of spilling the water when using the device in its capacity of a foot-bath. 25 30

I am aware that in sitting-bath tubs a portion has been extended upward as a back or rest for the person; but such a tub is of different construction, and is designed for a different, and will not effect the same, purpose as 35 that effected by my invention; and therefore I do not claim such a sitting-bath tub; but,

Having described my invention, I claim—

As a new article of manufacture, a foot-bath having one of its long sides extended upward 40 for its entire length and increasing in width as it rises by following the angle of the ends of the bath, substantially as and for the purposes specified.

JAMES S. HAGERTY.
